L. C. VANDERLIP.
PNEUMATIC CONVEYER.

APPLICATION FILED JULY 27, 1916. RENEWED NOV. 28, 1919.

1,346,144.

Patented July 13, 1920.

INVENTOR.
Louis C. Vanderlip.

UNITED STATES PATENT OFFICE.

LOUIS C. VANDERLIP, OF ELKHART, INDIANA.

PNEUMATIC CONVEYER.

1,346,144.

Specification of Letters Patent.

Patented July 13, 1920.

Application filed July 27, 1916, Serial No. 111,573. Renewed November 28, 1919. Serial No. 341,270.

To all whom it may concern:

Be it known that I, LOUIS C. VANDERLIP, a citizen of the United States, residing at Elkhart, county of Elkhart, State of Indiana, have invented new and useful Improvements in Pneumatic Conveyers, of which the following is a specification.

This invention relates to pneumatic conveyers wherein fluid under pressure, such as steam or compressed air, is introduced to a pipe conduit interior to convey loose and disintegrated materials such as ashes, sand, gravel, and the like.

An object of my invention is the production of an improved device of the class described which may be connected at both ends with straight piping for a conduit line for straight away conveyer work, thereby eliminating elbows, bends, &c., from the conveyer line. Another object of my invention is the provision of improved means for the introduction of fluid under pressure axially of a straight conveyer line, whether in a horizontal, perpendicular or inclined position. And another object is the production of a chambered fluid pressure nozzle carrier in which the fluid pressure chamber is flattened, or elongated, to reduce the transverse displacement of the nozzle carrier within the conveyer line. And still another object is the provision of means for protecting the nozzle carrier against wear due to the abrasive action of the materials conveyed. And a still further object of my invention is the enlargement, or bulging, of the main casing thereof adjacent the nozzle carrier to facilitate the movement of the materials past the nozzle carrier. Other objects will be mentioned and described from time to time herein.

The preferred embodiment of my invention is clearly shown on the accompanying drawings in which, Figure 1 is a longitudinal section in elevation; Fig. 2 is a section on the line 2--2 of Fig. 1; Fig. 3 is a section on the line 3--3 of Fig. 1; and Fig. 4 is a section on the line 4--4 of Fig. 1. Similar numerals of reference refer to similar members and parts of members throughout the several views on the drawings.

Referring to the drawings in detail, the numeral 1 indicates a channeled body member provided with suction intake opening 2 and an outlet opening 3 at the opposite end and preferably in axial alinement, and adapted to be introduced in a pipe conveyer line intermediate its extremities, or to have

a suction pipe fastened to intake opening 2 and a discharge pipe to opening 3. The numeral 4 indicates an opening formed in the wall of the member 1 to permit of the introduction of the nozzle carrier 5 provided with the projection 6 arranged within the interior of the member 1, and which is provided also with the steam chamber 7 which is flattened, or elongated, to minimize the transverse displacement of the carrier 5 and the projection 6 within the pipe member 1. The chamber 7 is also enlarged somewhat in area, in the direction of the elongation, to provide ample steam supply and the maximum pressure thereof at the steam nozzle hereinafter described. The upper end of the steam chamber 7 is provided with an inlet opening 8 which is in communication with a steam supply pipe 9 leading to any suitable source of steam. By elongating the steam chamber 7 and making the side walls thereof of reasonable thickness the projection 6 displaces the minimum space transversely of the member 1, thereby facilitating the movement of the conveyer contents past and around the projection 6. The numerals 10 and 11 indicate flanges of the nozzle carrier 5 adapted to be fastened to the base 12, of member 1, by bolts 13, 13, the flanges being suitably apertured for that purpose. The numeral 14 indicates an aperture formed in the projection 6 adjacent its lower end and adapted to receive and rigidly carry the steam nozzle 15 which is preferably placed in axial alinement with the opening 3 of member 1, and which is adapted to introduce the fluid under pressure to the conveyer pipe interior to create the necessary suction for the movement of the materials therethrough. The nozzle 15 may be fastened to the projection 6 in registration with the aperture 14 in any suitable manner, but the preferred method is by bolts, screws, or screw threads on that portion thereof within the opening 14. By having the issuing end of said nozzle 15 rigidly held in substantially axial alinement with the discharge opening 3 of the member 1 the wear on the pipe interior is uniform at the bore thereof and the maximum vacuum obtained for suction purposes with the minimum steam consumption.

The projection 6 of the nozzle carrier 5 is provided with an inclined, or slanting, wall 6' to which is detachably fastened the inclined wear plate 16, the latter being held in

position by a bolt, or screw, 17 engaging the flange 10. The wear plate 16 is provided with a forward extension portion 18 underlying the lower end of the projection 6 to protect the latter against abrasive action of the conveyer contents. The inclined wear plate 16 is provided with a pointed end by beveling the surface thereof as at 18', 18', as indicated in Fig. 4, to deflect the moving materials and to offer the minimum amount of resistance to the passage thereof. Being detachable the wear plate 16 may be removed and another substituted therefor when worn out. To further facilitate the passage of the materials past and around the projection 6, where coarse ashes and heavy clinkers are being handled by the conveyer, the bottom and side walls of the body member 1 are bulged outward at 19 and 20, respectively, adjacent the projection 6; thereby increasing the cross section area thereof.

A suitable hand hole may be made in the body member at any desirable location either for inspection thereof or for the introduction of tools to the interior thereof for any purpose.

I claim:

1. In a device of the class described, the combination with a channeled body member having suction intake and discharge openings substantially in axial alinement and provided with a hollow member projecting into the channel of said body member, said hollow member being adapted to introduce fluid under pressure into the channel of the body member and axially of said intake and discharge openings, of a buffer plate or wear member removably arranged in front of said hollow member and extending substantially to the end thereof.

2. A device of the class described comprising a channeled body member having suction intake and discharge openings and a lateral opening and a chambered member sealing said lateral opening and adapted to receive fastener members for detachably securing it to said body member said chambered member projecting into the channel of said body member and provided with an opening adapted to admit fluid under pressure thereto, said chambered member being provided also with an orifice adapted to admit fluid under pressure to said body member.

3. A pneumatic conveyer comprising a channeled body member having suction intake and discharge openings; a chambered member projecting into the channel of said body member, said chamber being provided with an opening adapted to admit fluid under pressure thereto, said chambered member being provided also with a fluid pressure outlet in communication with the interior of said body member; and a detachable wear plate disposed in front of said chambered

member and provided with a pointed wear taking surface.

4. A pneumatic conveyer comprising a channeled body member having suction intake and discharge openings; a chambered member projecting into the channel of said body member, said chamber being provided with an opening adapted to admit fluid under pressure thereto, said chambered member being provided also with a fluid pressure outlet in communication with the interior of said body member; and a detachable wear plate disposed in front of said chambered member and provided with beveled wear taking surfaces.

5. A pneumatic conveyer comprising a channeled member having suction intake and discharge openings and a lateral aperture; a flanged chambered member detachably sealing said lateral aperture and projecting into the channel of said body member, said chamber being elongated and provided with an opening adapted to admit fluid under pressure thereto, said chambered member being provided also with a second aperture in communication with the interior of the body member; and a nozzle carried by said chambered member, connected with said second aperture of said chambered member and adapted to establish communication between said chamber and the interior of said body member.

6. A pneumatic conveyer comprising a channeled member having suction intake and discharge openings and a lateral aperture; a flanged chambered member detachably sealing said lateral aperture and projecting into the channel of said body member, said chamber being elongated and provided with an opening adapted to admit fluid under pressure thereto, said chambered member being provided also with a second aperture in communication with the interior of the body member; a nozzle carried by said chambered member, connected with said second aperture of said chambered member and adapted to establish communication between said chamber and the interior of said body member; and a wear plate detachably disposed in front of said chambered member.

7. A pneumatic conveyer comprising a channeled body member having suction intake and discharge openings substantially in axial alinement and provided with a branch opening; and a flanged chambered member detachably sealing said branch opening and projecting into the channel of said body member, said chamber being provided with an opening adapted to admit fluid under pressure thereto, said chamber being provided also with a fluid pressure outlet in communication with the interior of said body member.

8. A device of the class described comprising a channeled body member having suc-

tion intake and discharge openings and a lateral opening; and a chambered member arranged within said body member lateral opening and provided with a flange which is 5 detachably fastened over said lateral opening, said chambered member projecting into the channel of said body member and provided with an opening adapted to admit

fluid under pressure thereto, and provided also with a second opening adapted to conduct fluid under pressure to the channel of 10 said body member.

In testimony whereof I have hereunto affixed my signature at Elkhart, Indiana, this 25th day of July, 1916.

LOUIS C. VANDERLIP.
